ENOCH RECTOR, OF NEW YORK, N. Y., ASSIGNOR TO RECTOR GASIFIER COMPANY, OF WAUKESHA, WISCONSIN, A CORPORATION OF WISCONSIN

OIL GAS CARBURETOR

Application filed April 19, 1929. Serial No. 356,324.

This invention relates to carburetors, and more particularly to carburetors of that class in which heavy fuel is subjected to heat treatment.

5 In using carburetors of various types, such as are now in common use, difficulty is frequently encountered due to condensation. Condensation is due largely to the fact that the fuel is delivered to the engine cylinder 10 in the form of a simple vapor mixed with air at atmospheric temperature, this resulting in condensation of the fuel on the cylinder walls and the formation of minute globules, causing appreciable loss due to the fact 15 that the fuel globules will not readily ignite and explode. This also renders it impossible to obtain a fuel mixture of uniform consistency and causes deposition of carbon in the cylinder.

20 Detonation, or premature explosion of the fuel mixture, is probably due largely to excessively high temperatures of the fuel in the form of a simple vapor. Various attempts have been made to overcome condensation by heating the fuel to a high temperature before it enters the engine cylinder. 25 These attempts have not met with any great success, as heating of the fuel to a high temperature increases rather than diminishes 30 detonation, as long as the fuel is supplied to the cylinder in the form of a simple vapor. In fact, my experiments indicate that it is impossible, from a practical standpoint at any rate, to prevent condensation when using heavy fuel so long as the fuel is delivered to the cylinder in the form of a simple vapor, even though the fuel in this form may 35 be heated to a high temperature. It is possible, however, to produce a thoroughly satisfactory fuel which is free from condensation and detonation by altering the physical and chemical properties of the liquid hydrocarbon ordinarily used in connection with internal combustion engines so as to produce 40 from such hydro-carbon fixed gases and a colloidalized vapor.

45 One of the main objects of my invention is to provide an apparatus, in the nature of a generator and a carburetor, by means of which the heavier hydro-carbons are sub-

jected to heat treatment in such manner as to produce fixed gases and a colloidalized vapor, these gases and the vapor being then mixed with air in proper proportion to produce an explosive mixture which is conducted to the 55 engine cylinder.

The vapor, being colloidalized, has characteristics similar to that of the fixed gases in that it is difficult to condense and will not readily condense when brought into contact 60 with the cylinder walls. The explosive mixture thus produced is highly efficient and avoids objectionable detonation.

I have found that to produce a colloidalized vapor from a hydro-carbon, the hydro-carbon should be heated with great rapidity. Apparently the rapidity of the rise or increase in temperature has more to do with colloidalizing the resulting vapor than the amount of 65 increase or rise in temperature. It is an object of my invention to provide means whereby the hydro-carbon is discharged in the form of a sheet or spray which is subjected, while in this form, to the action of highly heated inert gases which are brought into intimate 70 contact with the particles of the hydro-carbon spray and act to raise the temperature thereof to a relatively high value substantially instantaneously. This rapid increase in temperature of the hydro-carbon results in a cracking operation which converts a portion thereof into fixed gases, the remaining portion of the hydro-carbon being converted into 75 a colloidalized vapor. An additional object 80 of my invention is to provide a method and means for practicing the same whereby the heavier hydro-carbons can be efficiently converted into fixed gases and a colloidalized vapor, this conversion of the hydro-carbon 85 being carried on as a continuous operation and the product therefrom being mixed with air and continuously drawn off and conducted to a point of consumption. Further objects 90 and advantages of my invention will appear 95 from the detailed description.

In the drawings:

Figure 1 is a diagram of a generator and carburetor constructed in accordance with my invention, and associated parts;

Figure 2 is a plan view of my generator and carburetor, on an enlarged scale;

Figure 3 is a section taken substantially on line 3—3 of Figure 2;

5 Figure 4 is a section taken substantially on line 4—4 of Figure 3, parts being shown in elevation;

Figure 5 is a section taken substantially on line 5—5 of Figure 4;

10 Figure 6 is a section taken substantially on line 6—6 of Figure 4;

Figure 7 is a plan view of the cracking and mixing chamber, the casing and dome of the combustion chamber being removed;

15 Figure 8 is a fragmentary section taken substantially on line 8—8 of Figure 4; and

Figure 9 is a fragmentary section taken substantially on line 9—9 of Figure 7.

My carburetor comprises a lower cracking and mixing chamber 1, the outside of which is substantially cubiform, this chamber having an inner cylindrical space 2. Chamber 1 is closed, at its lower end, by a bottom plate 3 secured in position in a suitable manner, as 25 by means of cap screws 4.

This chamber is provided, through one side wall thereof, with an air inlet opening 5 which communicates with an air inlet chamber 6 secured in a suitable manner, as by 30 means of bolts 7, to the chamber 1. Air is admitted to chamber 6 through an air tube or horn 8 which is suitably secured at its upper end to the lower end of the chamber.

Chamber 1 is provided, at its upper end, 35 with an inwardly projecting wall forming a relatively thick shoulder 9 which is of hollow construction, forming a main fuel supply channel 10. Fuel is supplied to this channel, from a suitable source of supply such as tank 40 11 (Figure 1) through a pipe 12 connected to the discharge of a pump 13, the intake of which is connected by a pipe 13a to float chamber 11a. The pump 13 may be of any suitable type though ordinarily I preferably 45 use a diaphragm pump of known construction.

Shoulder 9 is provided in its upper face with an annular trough or depression 15, the central portion of this shoulder forming 50 an upwardly tapering head 16. A cap 17 fits upon this head and extends downwardly into the depression 15, this cap being provided at its lower edge with an outwardly projecting base flange 18, the outer edge of 55 which is spaced away from the inner face of the outer wall of the trough. The shoulder 9 is provided with openings 19 which establish communication between the fuel channel 10 and the trough or depression 15 at the 60 outer edge of flange 18.

This provides means for continuously supplying fuel to the depression 15.

The chamber 1 is provided, on the outer wall thereof and adjacent each corner, with 65 a vertically disposed rib 20 which is bored

out from its upper end to form a vertical overflow passage 21. These passages open, at their lower ends, into a passage 22 which extends about three sides of chamber 1. An overflow pipe 23 extends from the passage 70 22 and discharges into chamber 11a. Referring more particularly to Figure 7, the upper face of chamber 1 is milled out to provide inwardly flaring slots 24 extending from the depression 15 to the upper end of each of the vertical passages 21. As will be noted more particularly from Figure 9, the bottom wall of the slot 24 is disposed an appreciable distance above the bottom of the trough or depression 15. This provides means for maintaining the fuel in the depression 15 at a constant level, the overflow being returned to chamber 11a by the pipe 23.

A cylindrical casing 25 seats upon the upper face of chamber 1 and is secured thereto in a suitable manner, as by means of cap screws 26 passing through a base flange 27 of casing 25 and screwing into the upper end of chamber 1. This flange 27 is provided with suitably disposed elements which close 80 the upper ends of the vertical passages 21, the flange also covering the outwardly converging grooves 24.

The upper end portion of casing 25 contains an annular space 28 which constitutes a 95 reservoir. This space is concentric with an annular depression 29 in the upper face of casing 25 and extending about a tubular neck 30 of a dome shaped hood 31 which is disposed within casing 25 in concentric relation 100 thereto. This hood is secured in position by screws 32 which thread into the top wall of casing 25, or in any other suitable manner. Air inlet openings 33 are provided through the top wall of the casing and open into the 105 space 34 between the dome 31 and the casing. A fire screen 35, formed of wire gauze, extends across the upper end of depression 29 and is clamped between the top wall of the reservoir 28 and a spider 36 secured to this 110 wall by screws 37 or in any other suitable manner. This spider fits snugly about the upper reduced portion of neck 30 and also coacts with a shoulder on the neck for clamping the inner portion of the screen 35. The 115 spider is provided with suitably disposed openings 38 for admitting air above the screen 35. This spider is also provided with suitably spaced lugs 39 between which is hingedly secured a lug 40 of an annular frame 41, this frame comprising a clamping ring 42 secured in position by screws 43, which ring coacts with the frame proper for securing a closure 44 of glass or other suitable transparent material in the frame. This provides an 120 observation window through which the combustion space beneath the hood 31 can be observed.

An opening 45 establishes communication 125 between the interior of the casing 25 and 130

the gasoline reservoir 28. This opening is controlled by a needle valve 46 the body of which is threaded through the top wall of the reservoir. A tube 47 extends through the 5 top wall of the reservoir and is provided with a suitable valve 48. This tube may be connected to a suitable source of supply of gasoline, such as a tank. This provides means for periodically filling the reservoir 28 as required. If desired, the tube 47 may be replaced by a screw plug and the reservoir can be filled by hand as required. When first 10 starting the generator and carburetor, gasoline is supplied to the depression 15 by opening the valve 46. This gasoline is then ignited in a suitable manner, as by means of a spark plug 49 which screws into a boss 50 of casing 25, the electrodes of this plug being disposed within the combustion space beneath 15 the hood or dome 31.

As will be noted more clearly from Figure 3, the lower edge of the dome 31 is disposed closely adjacent the upper surface of the fuel in the depression 15, and this dome is provided with a plurality of vertically extending openings or slots 51, the spark plug 49 extending through one of such slots. A tube 52 is mounted through head 16 of wall 9 of chamber 1, the upper portion of this tube 25 being of increased thickness forming an outer annular shoulder which seats upon a similar shoulder formed in wall 9.

This tube extends downwardly to within a short distance of bottom plate 3 of chamber 1 and is disposed in concentric spaced relation to a sleeve 53 which is welded at its lower end, at 54, to plate 3 and extends upwardly therefrom to within a short distance of the under face of wall 9. A venturi 40 55 is threaded or otherwise suitably mounted in cap 17, centrally thereof, and extends downwardly into tube 52, this venturi also extending upwardly above the tube with its upper end substantially in the plane of the 45 upper ends of slots 51. The tube 52 is provided with a plurality of radially disposed fuel inlet openings 56 which communicate with a supplemental fuel channel 57 formed in the wall or shoulder 9 and extending 50 about the tube 52, these openings being an appreciable distance below the venturi 55. A manifold connecting member or stack 58, provided with a base flange 59, is secured to one face of chamber 1 in a suitable manner, as by means of cap screws 60. This face of the chamber is provided with an outlet opening which registers with the opening in the end of member 58, this member being provided at its other end with a flange 61 60 having lugs 62 provided with openings for securing this flange to a cooperating flange of an intake manifold of an internal combustion engine. This provides means for connecting the chamber 1 to a suitable suction 65 source.

Air inlet chamber 6 depends from and is formed integrally with a block 63. A float chamber 64 is cast integrally with this block, this chamber containing a float and a valve controlled thereby for maintaining fuel in 70 the chamber at a constant level. A fuel supply pipe 65 is connected to the chamber and may be connected to any suitable source of fuel supply, such as a tank, not shown. A vertical duct 66 (Fig. 5) is drilled in the block 63 from the upper face thereof, this duct being connected at its lower end, by an opening 67, with the float chamber 64 adjacent the lower end thereof. A sleeve 68 is screwed into the upper end of duct 66 and 80 is provided with radial air inlet ducts 69. This sleeve has the lower end portion of its bore reduced at 70 forming a valve seat 71 with which coacts a needle valve 72 for controlling the flow of air through the sleeve 85 into the duct 66. The body portion of valve 72 is threaded at 72a and screwed into the upper portion of sleeve 68, a hand wheel 73 being secured upon the upper end of the valve. This hand wheel is provided with a 90 depending neck 74 which carries a collar 75. This collar fits about the upper end portion of sleeve 68 and is secured in adjustment thereon by a set screw 76. The sleeve and the valve and associated parts constitute an 95 air bleed device for bleeding air into duct 66 in a known manner and for a known purpose. The block 63 is provided with a horizontal duct 77 extending from the upper end of duct 66 and opening into a bore 78 100 extending from the upper face of the block.

This bore is reduced in diameter at its lower end portion and extended downwardly to form a well 79 providing a shoulder 80 at the upper end of this well. A thimble 81 fits into bore 78 and seats upon the shoulder 80, the upper portion of this thimble being reduced in diameter to provide an annular fuel receiving space 82 about the thimble, this upper reduced portion of the thimble having 105 radially disposed fuel inlet openings 83. A bushing 84, screwed into the upper end of well 78, slidably receives a fuel control valve 85 which operates through the thimble 81. The lower end portion of this valve is cut 110 off at an inclination so as to be bevelled at 86 (Figure 3) and the body of the valve is of such diameter as to close the opening at the lower end of the thimble when the valve is in its full lowered position. It will thus be 115 seen that by raising and lowering the valve 85, the supply of fuel from the bore 78 to the well 79 can be regulated.

An elongated bushing 87 is secured in the block 63 and extends below the block to within a short distance of the air inlet member 8. An air control valve 88 is suitably secured, as by means of a nut 89, on a reduced threaded stud 90 at the lower end of a valve stem 91 which is slidably mounted in the bush- 120 125 130

ing 87. This valve controls the air inlet opening of member 8 and, when in full lowered position, completely closes this member. Downward movement of the valve is limited by a stop pin 91a threaded through a boss 92 formed integrally with member 8, this pin being secured in adjustment by a jam nut 93. Movement of valve stem 91 is regulated by a dash pot comprising a piston 94 suitably secured upon the upper end of stem 91, and a cylinder 95 within which the piston fits loosely in a known manner.

As will be noted more clearly from Figures 3 and 4, the block 63 is provided with a duct 98 which extends from well 79, the inner end of this duct being in register with the outer end of a duct 99 extending through a web 100 which bridges the main fuel supply channel 10 of chamber 1. This duct 99 is preferably provided with a liner 101, and opens into the supplemental fuel channel 57. An idler duct 102 (Fig. 6) extends from float chamber 64, adjacent the bottom thereof, at an upward inclination through the block 63 and opens, at its upper end, into a well 103 bored from the upper face of the block. A sleeve 104 screws into the upper end of this well and is provided with a reduced portion 105 which extends through the well 30 and fits snugly into a reduced bore 106 constituting a lower portion or extension of the well. A short duct 107 connects the lower end of bore 106 to duct 98. An elbow 108 screws into the upper end of sleeve 104 and 35 is provided with an air bleed device 109 similar to the air bleed for the main fuel supply duct 66. The ducts 66 and 102, and associated parts provide means for supplying fuel to the supplemental fuel supply channel 57 40 when the engine to which the carburetor is connected is operating under load and when it is idling.

A water float chamber 110 is secured to the outer face of air inlet chamber 6, this chamber being provided with a float control valve and having a water supply tube 111 connected thereto, this tube being connected to a suitable source of supply of water, such as a water tank.

50 Chamber 110 is provided with a duct 112 extending through its inner wall and opening into an inclined duct 113 extending through the upper portion of the wall of chamber 6. The upper end of duct 113 opens 55 into a vertical duct 114 drilled into block 63 from the under face thereof. The upper end of duct 114 is connected by a short passage 115 to a well 116 drilled from the upper face of block 63. An air bleed device 117, 60 similar in its general construction to device 109, screws into block 63 and controls the admission of air into the upper end of duct 114. A bushing 118 is mounted in the upper portion of well 116, this bushing having an opening in register with the passage 115. A

water control needle valve 119 operates in the bushing 118. This valve extends through the piston 94 of the dash pot and is provided at its upper end with an enlarged head 120 which fits into a corresponding recess in the upper face of the piston, valve 85 being provided with a similar head 121 which also fits into a recess in the upper face of the piston. A locking disc 122 fits upon the upper face of the piston, within the upper skirt or flange thereof, and is secured in position by a nut 123 which screws upon the upper end of valve stem 91. This provides simple and efficient means for securing the two valves to the piston for movement therewith. When the piston 94 of the dash pot is in its lowermost position, the air valve 88 is closed and the valves 85 and 119 are in their lowermost positions cutting off communication between space 82 and well 79, and duct 114 and well 116, respectively.

55 A duct 124 (Figure 4) extends from the lower portion of well 116 into a bore 125 which extends through a boss 126 of block 63. A pipe plug 127 screws into the boss and acts to normally close the outer end of the bore. A duct 128 extends from the bore 125 and opens into a groove 129 formed in the inner face of block 63, this groove opening into the inner end of duct 98. This provides 60 means for supplying water to the fuel flowing through duct 98. When the engine is idling and the air valve 88 is closed, no water is supplied to duct 98.

65 Referring more particularly to Figure 8, block 63 is provided with three ducts 130, 131 and 132 which are disposed in superposed relation and open into the fuel float chamber 64. Duct 130 opens into the main fuel channel 10, by means of a supplemental duct 130a 70 extending through the shoulder or wall 9 of chamber 1, the outer end of this duct being in register with the inner end of duct 130. Duct 131 is similarly connected by a duct 131a to channel 15 at the bottom thereof, and duct 132 is connected by a duct 132a to channel 15 adjacent the top thereof.

75 Under ordinary operating conditions fuel is supplied under pressure to the channel 10 by means of the pump 13 and, through the ducts 130a and 130 to the float chamber 64. The overflow from the float chamber passes through the ducts 132 and 132a to the channel 15 and then, by way of the grooves 24, to the overflow passages 21. If the pump 13 80 should fail, or it is not desired to use the pump for any reason, fuel can be supplied from the float chamber 64 to channel 15 through the ducts 131 and 131a, the fuel level in the float chamber being closely adjacent 85 the lower portion of duct 132. The float chamber thus provides a reserve of fuel for the channel 15, as well as providing a source of supply of fuel for the main fuel duct 66 90 and the idling duct 102.

This apparatus is particularly adapted for the use of heavy hydro-carbons, such as fuel oil. In the use of such fuel, when subjected to heat, it has been found that difficulty is frequently experienced from a tarry sediment which tends to collect in the channel or depression containing the fuel. To prevent this, I have provided a ring 133 which is mounted loosely about cap 17. A plurality of rollers 144 are mounted for free turning movement upon headed pins 145 secured in the ring 133. These rollers rest upon flange 18 of the cap and support the ring 133. During use of the device, the ring 133 turns about the cap 17, due to vibration, and the rollers act to elevate any tarry substances which tend to collect in the lower portion of the depression 15. These tarry substances at the upper portion of the rollers are removed therefrom by the air currents flowing over the surface of the fuel in the depression 15, the air passing over the upper portions of the rollers. This provides automatic means for preventing the accumulation of tarry substances in the depression or trough 15.

In the operation of the apparatus, gasoline is admitted into the space 34 (Fig. 3) by means of the needle valve 46 and opening 45, and flows downwardly into the trough 15. This gasoline is ignited, by means of the spark plug 49 and during the suction stroke of the engine a down draft is created which causes the products of combustion to be drawn downwardly through the venturi 55 into and through the tube 56. The air admitted through the opening 33 is sufficient to support combustion within the space beneath the dome 31, but is not sufficient to support combustion of the fuel which is drawn through the opening 56 by the downwardly flowing stream of hot gases. The combustion of the fuel beneath the dome produces hot inert gases, composed largely of carbon dioxide. These gases flow through the venturi 55 and into the tube 52 at high velocity inducing fuel through the openings 56, this fuel being discharged into the tube substantially radially thereof in the form of a spray which extends throughout the cross-area of the tube so as to form, in effect, a thin sheet of fuel in a finely sub-divided condition. The small particles of this sheet of fuel spray are subjected to the direct action of the downwardly flowing hot inert gases, these gases being heated to a relatively high temperature. This results in a cracking action which converts a portion of the fuel into fixed gases. Also, the small particles of fuel which are subjected to the direct action of the hot gases in intimate contact therewith have their temperature suddenly increased to a relatively high value, this sudden increase in temperature of these fuel particles resulting in producing a colloidalized vapor. This mixture of fixed gases and colloidalized vapor flows

downwardly through the tube 52 to the lower end thereof and is whipped upwardly about the lower end of the tube, flowing between the tube 52 and sleeve 63.

This whipping action is of importance as obtaining thorough mixing of the gases and vapor, the upward flow of this mixture serving to pick up any small particles of carbon which may be deposited upon the upper face of plate 3 in the sleeve 53. In this manner I prevent the accumulation of any appreciable quantity of carbon in the sleeve. The mixture of fixed gases and colloidalized vapor flows out of the upper end of the sleeve 53 into the interior space 2 of chamber 1 where it is mixed with air entering the chamber through the opening 5. This produces a combustible mixture which is highly efficient in internal combustion engines, this mixture flowing through the stack 58 into the intake manifold and to the engine cylinder.

It will be noted that the opening of the valve 88 is dependent upon the air tension or suction in the space 2 of chamber 1. It is also to be noted that the valves 85 and 119 are operated by the piston 94 of the dash pot in accordance with opening and closing of valve 88. In this manner the amount of fuel and water supplied to the supplemental fuel channel 57 is varied in accordance with the amount of air admitted to the cracking and mixing chamber. This provides an automatic control for the fuel and water which is actuated in accordance with the air flow through the air admission member 8, which assures the proper supply of fuel mixture of the proper characteristics to the engine at all times. The water which is supplied to the fuel in the channel 57 is projected therewith in spray form from the openings 56 so as to be subjected to the direct action of the hot gases flowing through the tube 52.

The water is thus rapidly converted into steam and is intimately intermixed with the fuel in such manner as to provide a fuel mixture which contains a desirable amount of moisture sufficient to prevent the forming of carbon in the cylinder. I have found that by subjecting the water in spray form, and intimately intermixed with the fuel, to the action of the hot gases flowing through tube 52, the resulting steam is colloidalized or placed in such condition that it does not condense on the walls of the cylinder and associated surfaces. As a result, it is possible to employ water, in the form of steam, with the fuel, without causing corrosion or rusting of the cylinder walls such as occurs where water is merely sprayed into the fuel as it flows through the intake manifold or is admitted into the cylinder in the form of a simple vapor.

I have found that the provision of the main fuel supply channel 10 in the chamber 1 is particularly advantageous when using

heavy hydro-carbon, such as fuel oil. This is especially true during cold weather when the oil tends to thicken. After the device has been in operation for a short time, the oil in channel 10, even in extremely cold weather, is heated to a sufficiently high temperature so as to readily flow through the openings 19 into the depression 15. This facilitates combustion of the fuel and mixing thereof with the air current flowing across the top surface of the fuel in channel 15 and is advantageous at all times, particularly when using heavy fuel in cold weather.

Referring to Figure 1, it will be noted that the outlet of tank 11 is not connected directly to the intake of pump 13, but is connected by pipe 11' to the bottom of float chamber 11a, and the intake of the pump is connected to chamber 11a, above the bottom thereof, by a pipe 13a. The admission of oil from pipe 11' to chamber 11a is controlled by a needle valve 11c actuated by a float 11b within the chamber, in a known manner. This assures that the oil in float chamber 11a is at all times maintained at the proper level to provide an adequate supply of oil to the intake of pump 13.

An important feature of my invention, is the return to float chamber 11a of the oil which overflows from depression 15. This oil is quite hot and circulates through pipe 23, chamber 11a, pipe 13a, pump 13, pipe 12, channel 10, depression 15, passages 21 and 22, and thence back to pipe 23 in a continuous circuit so that the oil in float chamber 11a is maintained at a relatively high temperature. The amount of oil admitted from pipe 11' to chamber 11a is only that required to replace the oil which has been evaporated in the operation of the apparatus. It will thus be seen that the amount of oil which enters the float chamber 11a from pipe 11' at any given moment is quite small relative to the volume of hot oil in the float chamber. The small quantity of entering oil immediately commingles with the hot oil in the float chamber and has its temperature raised thereby to that of the oil in the chamber. The portion of pipe 11' adjacent chamber 11a is heated by conduction from the chamber and the hot oil therein, so that the oil in this portion of the pipe is heated sufficiently to readily flow into the chamber upon opening of the valve 11b.

This portion of pipe 11' may, therefore, be considered as a well containing readily flowing oil which is maintained under pressure by a column of thicker or more viscous oil in the remaining portion of pipe 11' and tank 11.

It will be noted that float chamber 11a is below the passages 22 and above the intake of pump 13, tank 11 being a considerable distance above the float chamber. I thus obtain gravity feed from passages 22 to the float chamber, from the float chamber to the pump,

and from the main fuel supply tank 11 to the float chamber. An important feature of my invention is that the oil which circulates through the float chamber and the pump is maintained hot and flows readily. This is of particular value when using the heavier hydrocarbons, such as fuel oil, which are viscous and do not flow readily unless heated. In cold weather, particularly, great difficulty is frequently experienced in using fuel oil, and other heavy hydrocarbons, due to the fact that such fuels become quite thick and viscous when cold. I avoid this difficulty by heating the oil and causing it to flow in a continuous circuit which includes a source of heat thus maintaining the oil in this circuit at a relatively high temperature, and introducing into this hot oil relatively small quantities of relative cool oil from an exterior source, as required. This method of treating oil or other liquid fuel to condition it for flow and for use in a burner, I believe to be broadly new. While I have illustrated and described this feature of my invention as applied to a gas generating and carbureting apparatus, by way of example, it can be used to advantage in many other apparatuses and I do not, therefore, limit my method to this one use but reserve the right to use it with any apparatus to which it may be advantageously applied.

In the operation of the engine to which the carburetor is attached, considerable vibration is produced. This vibration is transmitted to the carburetor and causes turning movement of the ring 133 about cap 17, such movement of the ring imparting turning movement of the rollers. The ring 133 and rollers 144 may be considered as, in some respects, analogous to a wick for facilitating the evaporation of the oil in depression 15. The upper portions of the rollers are at the top of the oil and are exposed to the heat of combustion within hood 31 so that the thin film of oil on these rollers is readily evaporated. As the rollers turn continuously I provide, in effect, a thin film of oil which is continuously replenished and is exposed to the heat of combustion so as to be rapidly evaporated thereby. Also, the oil above ring 133 is disposed in a thin layer and is readily evaporated by the heat of combustion within hood 31, supplemented by the heat of the ring which is maintained at a comparatively high temperature, from cap 17 and rollers 144, by conduction. I have illustrated the rollers 144 as supporting ring 133, by way of example, as a convenient means of causing these rollers to turn in the particular embodiment of my invention shown. In its broader aspects, however, my invention comprehends rollers or equivalent members which dip into the fuel and are caused to turn or rotate in a suitable manner to provide, in effect, a thin layer or film of the fuel which may be readily vapor-

ized for producing a combustible mixture. This I believe to be broadly new, not only in the particular embodiment herein illustrated, but in general.

5 The ducts 132 and 132a establish communication between the fuel float chamber 64 and the space in the combustion chamber so that the float chamber above the fuel level therein is subject to the suction in the combustion 10 chamber. This is of advantage as equalizing pressure in the float chamber, since the float chamber is in communication with tube 52 through the opening 56, channel 57, ducts 99 and 129 and associated parts. This equalization of pressure assures proper flow of fuel 15 from the float chamber through the ducts 66 and 77.

What I claim is:—

1. In a carburetor of the character described, a combustion chamber, a cracking and mixing chamber, a tube establishing communication between said chambers, means for connecting the mixing and cracking chamber to an intake manifold of an internal 25 combustion engine, and means for projecting liquid fuel across the tube in a sheet disposed substantially radially thereof, the fuel being metered by the products of combustion flowing therethrough from said combustion chamber.

2. In a carburetor of the character described, a combustion chamber, a cracking and mixing chamber, a tube establishing communication between said chambers, intermediate the ends thereof, means for supplying liquid fuel to said tube 35 for connecting the cracking and mixing chamber to a source of suction.

3. In a carburetor of the character described, a combustion chamber, a cracking and mixing chamber, a tube establishing communication between said chambers and provided with fuel inlet openings, means for connecting the mixing and cracking chamber 40 to a suction source, valve controlled means for admitting air to the mixing and cracking chamber in quantities varying in accordance with variations in the suction therein, and means controlled by said valve controlled 45 means for supplying fuel to said openings in quantities varying in accordance with variations in the quantity of air admitted to the mixing and cracking chamber.

4. In a carburetor of the character described, a combustion chamber having a depression for reception of liquid fuel, means for supplying fuel to said depression, a mixing and cracking chamber, a tube establishing communication between said chambers 55 and having fuel inlet openings, means for connecting the mixing and cracking chamber to a suction source, an air inlet member connected to said mixing and cracking chamber, a yielding valve controlling the inlet opening 60 of the air inlet member, means for supplying

fuel to the inlet openings of the tube, and valve means connected to the air valve for regulating the amount of fuel supplied to said tube inlet openings in accordance with opening and closing of the air valve. 70

5. In a carburetor of the character described, a combustion chamber, a cracking and mixing chamber, a tube establishing communication between said chambers and having fuel inlet openings, means for connecting the cracking and mixing chamber to a suction source, an air inlet member connected to the cracking and mixing chamber, a yielding valve controlling the outlet opening of said air inlet member, means for supplying fuel and water to the inlet openings of the tube, and valve means connected to the air valve and controlling the amounts of fuel and water supplied to said tube inlet openings in accordance with opening and closing 85 of the air valve.

6. In a carburetor of the character described, an upper combustion chamber having a fuel receiving depression at its lower end, a lower cracking and mixing chamber, a tube establishing communication between said chambers and having fuel inlet openings disposed substantially radially thereof, means for connecting the lower chamber to a suction source, an air inlet member connected to the lower chamber, a yielding valve controlling the inlet opening of said member, the upper chamber having air admission means, means for supplying liquid fuel to said depression and for maintaining it at a substantially constant level, deflecting means for causing air entering the upper chamber to pass over the surface of the fuel in said depression, means for supplying liquid fuel to the inlet openings of the tube, and means actuated by the air inlet valve for regulating the quantity of fuel supplied to said tube inlet openings in accordance with opening and closing of said air valve. 100

7. In a carburetor of the character described, an upper combustion chamber having a fuel receiving depression at its lower end and provided with air inlet openings, a lower cracking and mixing chamber, a tube establishing communication between said chambers and having fuel inlet openings disposed substantially radially thereof, a dome extending downwardly in the upper chamber and disposed over the tube with its edge adjacent the top surface of fuel in said depression, means for connecting the lower chamber to a suction source, means for admitting air to the lower chamber, and means for supplying fuel to the inlet openings of the tube. 110

8. In a carburetor of the character described, an upper combustion chamber having a fuel receiving depression at its lower end and provided with air inlet openings, a dome closed at its upper end and extending 115 downwardly within the upper chamber with 120

its lower edge adjacent the upper surface of fuel in said depression, means for supplying fuel to said depression and maintaining it at a substantially constant level therein, a lower cracking and mixing chamber, a sleeve extending upwardly within the lower chamber from the bottom wall thereof, a tube extending into the sleeve and establishing communication between said chambers and having its upper end beneath the hood, a venturi extending into the upper end of the tube and above the sleeve, said tube having substantially radially disposed fuel inlet openings below the venturi, means for connecting the lower chamber to a suction source, and means for supplying fuel to the inlet openings of the tube.

9. In a carburetor of the character described, a lower chamber having an inwardly projecting shoulder at its upper end, the shoulder being hollow for a portion of its extent defining a main fuel receiving channel, said shoulder having a fuel receiving depression in its upper face and openings establishing communication between said trough and the channel, a casing mounted on the top of the lower chamber and forming therewith an upper chamber, said casing having air inlet openings, a tube mounted through said shoulder and extending downwardly into the lower chamber, the tube establishing communication between said chambers, means for connecting the lower chamber to a suction source, controlled means for admitting air to the lower chamber, the shoulder having a supplemental channel extending about the tube and said tube having fuel inlet openings communicating with the second channel, means for supplying fuel under pressure to the main channel, and means for supplying fuel to the supplemental channel.

10. In a carburetor of the character described, a lower chamber, an upper combustion chamber, a wall separating the two chambers and defining a main fuel receiving channel, means for supplying fuel from said channel to the combustion chamber, a tube extending through said wall and establishing communication between the two chambers, said tube having fuel inlet openings, means for supplying fuel to said fuel inlet openings, means for connecting the lower chamber to a suction source, and controlled means for admitting air to the lower chamber.

11. In a carburetor of the character described, a combustion chamber, a cracking and mixing chamber, a wall separating the two chambers and hollow for a portion of its extent defining a main fuel supply channel, said channel communicating with the combustion chamber for supplying fuel thereto, means establishing communication between the two chambers, and means for connecting the cracking and mixing chamber

to a suction source, the combustion chamber having air inlet openings.

12. In a carburetor of the character described, a combustion chamber, a cracking and mixing chamber, a wall separating the two chambers and hollow for a portion of its extent defining a main fuel supply channel, said channel communicating with the combustion chamber for supplying fuel thereto, a tube passing through the wall and establishing communication between the chambers, said tube having radial fuel inlet openings, means for supplying fuel to said openings, the combustion chamber having air inlet openings, and means for connecting the cracking and mixing chamber to a suction source.

13. In a carburetor of the character described, an upper combustion chamber, a lower cracking and mixing chamber having an inwardly projecting shoulder at its upper end, said shoulder being hollow and defining a main fuel supply channel, the shoulder having a depression in its upper face and openings establishing communication between the channel and the depression, a tube mounted through the shoulder and establishing communication between said chambers, a cap mounted upon the upper face of the central portion of the shoulder and depending into the depression, said cap having an outer annular base flange, a venturi secured in the cap and extending into the tube, a ring disposed loosely about the cap, rollers mounted on the ring and bearing on said flange, said tube having fuel inlet openings below the venturi and the combustion chamber having air inlet openings, means for supplying fuel to said fuel inlet openings, controlled means for admitting air to the lower chamber, and means for connecting said lower chamber to a suction source.

14. In a carburetor of the character described, a combustion chamber having air inlet openings and comprising a fuel receiving depression, a ring disposed in said depression for free turning movement therein, and rollers mounted on the ring and contacting the bottom wall of the depression, the ring being supported by said rollers.

15. In a carburetor of the character described, a combustion chamber having air inlet openings and comprising a fuel receiving depression, a ring disposed in said depression for free turning movement therein, rollers mounted on the ring and contacting the bottom wall of the depression, the ring being supported by said rollers, and a dome having its lower edge portion adjacent the rollers, the dome being within the chamber and spaced from the walls thereof and said chamber having air inlet openings communicating with the space about the dome.

16. In combination, a combustion chamber comprising a fuel depression, a cracking

- and mixing chamber communicating with the combustion chamber and comprising a fuel channel communicating with said depression, and means for connecting the cracking and mixing chamber to a suction source. 5
17. In combination in means for conditioning liquid fuel for flow and combustion, a combustion chamber comprising a fuel receiving depression, means for taking off hot liquid fuel from the depression and for circulating it through a system and returning it to the depression, and means for introducing into the system relatively small quantities of liquid fuel from an exterior source. 10
18. In combination in means for conditioning liquid fuel for flow and combustion, a combustion chamber comprising a fuel receiving depression having an overflow, means for taking off hot liquid fuel which overflows from the depression and for circulating it through a system and returning it to the depression, and means for introducing into the system relatively small quantities of liquid fuel from an exterior source. 15
19. In combination in means for conditioning liquid fuel for flow and combustion, a combustion chamber comprising a fuel receiving depression, an oil supply channel adjacent the depression and communicating therewith, said depression having an overflow, means for taking off the oil overflowing from the depression and for circulating it through a system and returning it to the depression, and means for introducing into the system relatively small quantities of oil from an exterior source. 20
20. In combination in means for conditioning liquid fuel for flow and combustion, a combustion chamber comprising a fuel receiving depression having an overflow, a float chamber, means for conducting the overflow from said depression to the float chamber, means for withdrawing oil from the float chamber and for delivering it to the fuel receiving depression, a source of supply of oil under pressure connected to the float chamber, and a float controlled valve in the chamber for controlling the admission of oil from said source of supply. 25
21. In combination in means for conditioning liquid fuel for flow and combustion, a combustion chamber comprising a fuel receiving depression having an overflow, a float chamber at a lower level than said depression, means for conducting the overflow from the depression to the float chamber, a pump having its intake at a lower level than and connected to the float chamber, the discharge of the pump being connected to the fuel receiving depression, a source of supply of fuel under pressure connected to the float chamber, and a float controlled valve in the float chamber for controlling the admission of fuel from said source of supply. 30
22. In combination in means for condition- ing liquid fuel for flow and combustion, a burner, means for withdrawing hot fuel from the burner and for circulating it through a system and returning it to the burner, and means for introducing into the system relatively small quantities of liquid fuel from an exterior source. 35
23. In a carburetor of the character described, an upper combustion chamber, a lower chamber, a tube establishing communication between said chambers and provided with fuel inlet openings intermediate its ends, means for supplying liquid fuel to said openings, and means for connecting the lower chamber to a source of suction. 40
24. In a carburetor of the character described, an upper combustion chamber, a lower chamber communicating with the upper chamber through a restricted passage provided with fuel inlet openings intermediate its ends, means for supplying liquid fuel to said openings, and means for connecting the lower chamber to a source of suction. 45
25. In a carburetor of the character described, an upper combustion chamber having a fuel receiving depression at its lower end and provided with air inlet openings, a lower chamber, a tube establishing communication between said chambers and provided with fuel inlet openings, a dome extending downwardly in the upper chamber and disposed over the tube with its lower edge adjacent said depression, and means for connecting the lower chamber to a source of suction. 50
- In witness whereof, I hereunto subscribe my name this 13th day of April, 1929.
- ENOCH RECTOR.
